(57) **CLAIM**

The ornamental design for an upper for a shoe, as shown and described.

DESCRIPTION

FIG. 1 is a perspective view of an upper for a shoe in accordance with my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines in FIGS. 1–6 depict a shoe sole environment, which forms no part of the claimed design. The other broken lines and the area within the broken lines in FIG. 6, show portions of the shoe interior, which also forms no part of the claimed design.
